United States Patent Office

Des. 204,456
Patented Apr. 19, 1966

204,456

CABLE SPACER

Arthur R. Mason, Haywards Heath, Sussex, England,
assignor to Bowthorpe Engineering Company Limited,
Crawley, England

Filed Aug 3, 1964, Ser. No. 81,132

Term of patent 14 years

(Cl. D26—1)

FIG. 1.

FIG. 2.

FIG. 3.

FIGURE 1 is a front elevational view of a cable spacer showing my new design;

FIGURE 2 is a bottom plan view thereof; and

FIGURE 3 is a top plan view thereof.

The rear, not shown, is identical to the front, shown in FIGURE 1.

I claim:

The ornamental design for a cable spacer, as shown and described.
